RAIL JOINT.

1,427,739.

Specification of Letters Patent. Patented Aug. 29, 1922.

Application filed May 29, 1922. Serial No. 564,437.

To all whom it may concern:

Be it known that we, FRANK E. HUSS and WALTER W. MOMSEN, citizens of the United States, residing in the city of Belleville, 5 county of St. Clair, and State of Illinois, have invented a certain new and useful Improvement in Rail Joints, of which the following is a full, clear, and exact description, such as will enable others skilled in the art 10 to which it appertains to make and use the same.

This invention relates to rail joints, and has for its object to provide an efficient rail joint of simple design that is easy to 15 install and of such construction that it will securely hold two abutting rails in longitudinal alignment with each other and prevent the end portions of said rails from moving vertically relatively to each other 20 and relatively to the joint when a load passes over the joint.

Figure 1 is a side elevational view of our improved rail joint, showing the removable member of the joint partly broken away.

25 Figure 2 is a vertical transverse sectional view of said joint; and

Figure 3 is a side elevational view, showing the stationary rail engaging member of the joint that extends longitudinally at one 30 side of the rails.

Referring to the drawings which illustrate the preferred form of our invention, A designates a horizontally-disposed base plate that is adapted to support two abutting rails α , B designates a stationary rail engaging member integrally connected to said base plate and arranged longitudinally at one side of the rails, and C designates a removable rail engaging member detachably 35 connected to the base plate A and arranged longitudinally at the opposite side of the rails. The stationary rail engaging member B is provided with a vertically-disposed web 1, a rail flange engaging portion 2 at the lower edge of said web that laps over and bears against the top faces of the base flanges of the rails and a rail head engaging portion 3 at the upper edge of said web that bears against the underside of the 40 heads of the rails, as shown in Figure 2, said rail flange engaging portion 2 being integrally connected at its outer edge to the base plate A. The removable rail engaging member C is similar in general design to the 45 stationary rail engaging member B and comprises a vertical web 1 α , a rail flange 50

engaging portion 2 α at the lower edge of said web and a rail head engaging portion 3 α at the upper edge of said web. The top faces of the portions 3 and 3 α that bear 55 against the underside of the heads of the rails are so formed that they bear against said rail heads at points some distance away from the webs of the rails, as shown in Figure 2, when the joint is first installed, 60 thereby permitting the wear on the rail engaging members B and C and on the rails to be taken up or compensated for by tightening the nuts on the bolts of the joint so as to draw the members B and C inwardly 65 towards the webs of the rails. In the form of our invention herein illustrated the removable rail engaging member C is provided at its lower end with a plurality of depending devices 4 of substantially hook 70 shape in general outline, as shown in Figure 2, and the base plate A is provided with openings or recesses 5 into which the hook-shaped devices 4 on the member C are adapted to be inserted, each of said openings 75 or recesses having an inclined wall 5 α that laps over an outwardly-projecting portion of the hook-shaped device 4 so as to prevent the member C from moving upwardly relatively to the base plate. The devices 4 80 are so proportioned that they do not project downwardly below the bottom face of the base plate A, and consequently, in installing the joint it is not necessary to space the ties in any particular relation or cut or 85 notch out the top faces of the ties, due, of course, to the fact that the underside of the joint is flat and free of downward projections throughout its entire area. Moreover, as the devices 4 have laterally-projecting 90 portions provided with inclined top faces that bear against inclined surfaces 5 α on the base plate, the operation of tightening the joint bolt nuts causes the devices 4 on the member C to rock upwardly in such 95 a way that they exert pressure on the base plate A in a direction tending to force it tightly against the underside of the base flanges of the rails.

To install the joint, the rails α are arranged in longitudinal alignment with each other on the base plate A in such a manner that the portion 2 of the member B will bear against the top faces of the base flanges of the rails and the portion 3 of said member 100 will bear against the underside of the heads of the rails. The removable rail engaging 110

member C is then arranged in operative position by inserting the hook-shaped devices 4 or same in the openings 5 in the base plate A and moving said member C into engagement with the base flanges and the heads of the rails. Thereafter bolts 6 or other suitable retaining devices are passed transversely through holes in the webs of the members B and C and in the webs of the rails, the holes in the webs of the rails being elongated, as shown in Figure 1, so as to provide for the longitudinal expansion and contraction of the rails. The holes 6^a in the web of the stationary rail engaging member B that receive the bolts 6 are preferably of such form that they will co-operate with lugs or ribs 6^b on the shanks of the bolts, as shown in Figures 2 and 3, to prevent said bolts from turning when the nuts on the bolts are tightened.

A rail joint of the construction above described is inexpensive to manufacture, as it consists simply of two rugged castings; it is easy to install and it will securely hold two rails in longitudinal alignment with each other and prevent the end portions of the rails from moving vertically relatively to each other or relatively to the joint, due to the fact that the rails are supported rigidly by the base plate and are held securely throughout the entire length of said base plate by two rail engaging members that are clamped snugly between the base flanges and the heads of the rails and which are combined with the base plate in such a manner that they cannot move vertically relatively to the base plate. When the joint is first installed the rail engaging members B and C stand in the position indicated by dotted lines in Figure 2, but after

the joint has been in use for some time, the nuts on the bolts 6 are tightened so as to draw the members B and C inwardly into the position shown in full lines in Figure 2, so as to take up the wear on the co-operating surfaces on the rails and on the members B and C of the joint.

Having thus described our invention, what we claim as new and desire to secure by Letters Patent is:

A rail joint, comprising a stationary member provided with a base plate having an integral rail engaging member at one side of the rails, a removable rail engaging member at the opposite side of the rails, portions on said rail engaging members bearing against the underside of the heads of the rails and so formed that they are adapted to be drawn inwardly towards the webs of the rails to compensate for wear on said portions and rail heads, depending devices on said removable rail engaging member projecting downwardly into holes in the base plate and terminating flush with the underside of the base plate, laterally-projecting portions on said devices having inclined top faces that bear against co-operating inclined faces on said base plate, and means for drawing said rail engaging members inwardly towards the webs of the rails so as to compensate for the wear on the rail head engaging portions of same and to cause the depending devices on the removable rail engaging member to exert upward pressure on the base plate in a direction tending to hold it tightly against the underside of the base flanges of the rails.
